US00D671947S

(12) **United States Design Patent**
Akana et al.

(10) **Patent No.:** US D671,947 S
(45) **Date of Patent:** ** Dec. 4, 2012

(54) **HOUSING FOR AN ELECTRONIC DEVICE**

(75) Inventors: **Jody Akana**, San Francisco, CA (US); **Bartley K. Andre**, Menlo Park, CA (US); **Jeremy Bataillou**, San Francisco, CA (US); **Sean Stewart Corbin**, San Jose, CA (US); **Daniel J. Coster**, San Francisco, CA (US); **Daniele De Iuliis**, San Francisco, CA (US); **Jeremy Contini Franklin**, San Francisco, CA (US); **Kevin David Gibbs**, Menlo Park, CA (US); **Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Stephen McClure**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/385,793**

(22) Filed: **Feb. 18, 2011**

(51) **LOC (9) Cl.** **14-02**

(52) **U.S. Cl.** **D14/439**

(58) **Field of Classification Search** ..... (57) **CLAIM**

The ornamental design for a housing for an electronic device, as shown and described.

DESCRIPTION

FIG. 1 is a bottom front perspective view of a housing for an electronic device showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The shade lines in the Figures show contour and not surface ornamentation.

1 Claim, 6 Drawing Sheets
